UNITED STATES PATENT OFFICE.

LEO JNO. BAYER, OF ST. LOUIS, MISSOURI, ASSIGNOR TO BAYER STEAM SOOT BLOWER COMPANY, OF ST. LOUIS, MISSOURI, A CORPORATION OF MISSOURI.

SOOT-BLOWER FOR BOILERS.

1,317,345.

Specification of Letters Patent. Patented Sept. 30, 1919.

Application filed November 16, 1917. Serial No. 202,348.

To all whom it may concern:

Be it known that I, LEO JOHN BAYER, a citizen of the United States, residing at St. Louis, State of Missouri, have invented certain new and useful Improvements in Soot-Blowers for Boilers, of which the following is a full, clear, and exact description, reference being had to the accompanying drawings, forming a part hereof.

- 10 The present improvement is particularly directed to soot blowers (sometimes called boiler cleaners) intended to operate in conjunction with a type of water-tube boiler known as the "Stirling boiler" in which two 15 or more (usually three) transversely disposed, parallel steam-and-water drums are connected with a single mud drum by means of water circulating tubes leading from the bottoms of each of the steam - and - water 20 drums to the top of the mud drum, the steam space of the center drum being connected to both the front and rear drums (where three drums are used) by a row of steam circulating tubes, and being connected to the water 25 space of the front drum by water circulating tubes, the number of which tubes depend on the class of boiler. The center drum being the highest, the steam outlet is placed on the top of this drum. In this type of boiler 30 (and assuming we are dealing with one having three steam-and-water drums) the fire gases flow from front to rear, making four passes after leaving the fire box, these passes depending on the disposition of the baffles in 35 the furnace of the boiler. As a rule these baffles are disposed on the rear tubes of the first and second banks, reaching in the first instance from the mud drum to a point above the center of the first or front bank, and in 40 the second instance from the center steam-and-water drum to a suitable point above the mud drum but very nearly to the bottom of said second or middle bank. A deflecting shelf is placed near the top of the front baffle, said shelf projecting rearwardly and substantially at right angles to the front baffle and terminating a suitable distance from the 45 second or middle bank of tubes. A second shelf is placed near the top of the rear or third bank of tubes and deflects the gases in their passage upward through said bank, toward the tubes, thus preventing by-passing between the tubes and the rear wall of the boiler setting. A fire brick baffle directly 50 over the water-circulating tubes between the front and middle steam-and-water drums prevents the gases passing above these tubes. The foregoing represents the general arrangement of a Stirling boiler; and since a single mud drum is connected with a series 60 of three steam-and-water drums, the several banks of water-tubes necessarily must radiate or pitch from said mud-drum at different angles (to the vertical) to reach their respective steam-and-water drums, these various 65 inclinations or pitches necessitating each a special disposition of blower nozzles to effect a thorough and complete blowing or cleaning of the boiler along the several passes traversed by the fire gases. It is therefore 70 the object of my invention to effect such a coördinated disposition of blower nozzles relative to the several banks of water tubes involved in the construction of a boiler of this type, that not only will the soot and 75 other accumulations be effectively dislodged from the heating surfaces to which such material may adhere, but the same shall be carried toward the gas outlet flue of the furnace without in any wise disturbing the general 80 line of draft defined by the passes followed by the fire gases. The advantages of the invention will be apparent from a detailed description thereof in connection with the accompanying drawings, in which— 85
- Figure 1 represents a side elevation of a Stirling boiler setting, showing the several banks of circulating water tubes and the baffles in dotted outline; and showing my improved soot blower in side elevation applied to the boiler; Fig. 2 is an enlarged vertical cross-section through the boiler setting on the line 2—2 of Fig. 1 showing in front elevation the so-called second blower unit, the same being broken at the middle; Fig. 3 is a 90 middle vertical longitudinal section through the blower unit shown in Fig. 2; Fig. 4 is a vertical cross-section on the line 4—4 of Fig. 3; Fig. 5 is a vertical cross-section on the line 5—5 of Fig. 3; Fig. 6 is a vertical cross-section on the line 6—6 of Fig. 3; Fig. 7 is an inner end view of the blower unit shown in Figs. 2 and 3; Fig. 8 is a top plan of the first or front bottom unit, the walls of the setting being in horizontal section taken on the line 8—8 of Fig. 1; Fig. 9 is a vertical longitudinal section of the first unit on the line 9—9 of Fig. 8; Fig. 10 is an enlarged vertical cross-section on the line 10—10 of Fig. 9; Fig. 11 is an enlarged horizontal sec- 105 110

tion on the line 11—11 of Fig. 1 showing the rotatable jet-pipe at the center of the middle bank of tubes; Fig. 12 is an inner end elevation of Fig. 11, the baffle being in section; 5 Fig. 13 is a front end view of the rotary jet pipe shown in Figs. 11 and 12 or a view looking through the second bank of tubes toward the middle baffle; Fig. 14 is an enlarged middle horizontal section of the gear 10 case in which is housed the gear joint by which the jet-pipe of the third blower unit is actuated; Fig. 15 is an enlarged horizontal section on the line 15—15 of Fig. 1; and Fig. 16 is a vertical longitudinal sectional 15 detail on the line 16—16 of Fig. 15.

Referring to the drawings, F represents the boiler setting, B the fire box, 1, 2, 3, the front, middle, and rear shells or steam-and-water drums respectively, 4, the mud drum, 20 5 the front bank of circulating water-tubes connecting the shell 1 with the mud-drum, 6 the middle bank of water-tubes, 7 the rear bank of water-tubes, 8 the steam tubes connecting the front and middle shells, 9 the 25 steam tubes connecting the middle and rear shells, 10 the water circulating tubes between the shells 1 and 2, and 11 the tiling or baffle directly over the tubes 10. The front baffle 12 carried by the rear members 30 of the front bank of tubes 5 is provided with a shelf 13 at a point below but adjacent to the upper end of the baffle, the middle baffle 14 disposed on the rear of the middle bank of tubes 6 reaching from the 35 shell 2 to a point near the bottom of said bank and above the mud-drum, and the baffle 15 at the rear of the rear bank of tubes 7 closing the opening between said bank and the rear wall of the boiler setting, 40 the upper end of said baffle terminating a suitable distance below the shell 3. The baffle 15 is in the form of an angle bar, the horizontal leg thereof engaging the rear wall of the boiler setting and preventing by- 45 passing of the gases between said wall and the rear bank of tubes 7. The foregoing features are well understood in the art and form no part of the present invention. The arrows in Fig. 1 represent the general course 50 of the furnace gases and combustion products, the same traveling from front to rear and making practically four passes, to wit: (1) upwardly from the fire-box B through the bank of tubes 5 over the front baffle 12 55 and around the shelf 13; (2) downwardly through the middle bank of tubes 6 below the lower edge of the middle baffle 14; (3) upwardly through the rear bank of tubes 7 over the top of the rear baffles 15; and (4) 60 downwardly and horizontally through the exit or outlet opening E, the gases of course always traveling rearwardly and playing over the heating surfaces of the shells 1, 2, 3, and the circulating tubes 10, 65 and T, the latter designating the several

tubes included in the respective banks 5, 6, and 7.

To properly "blow" or clean a boiler of this character, due regard must be had not only for the disposition of the several banks 70 of tubes T, but for the course or general direction of the fire gases or draft, the blower nozzles or jets being so arranged that the general line of draft shall not be disturbed; otherwise there would be danger of banking or backing the fire. This point will be clearly brought out when we come to consider the disposition of the several blower units as here constructed. P, represents the steam or cleaning-fluid supply-pipe, the 80 same being preferably coupled to the middle or highest shell 2, the steam therein being usually dry. Any other source of steam supply can however be availed of if necessary or convenient. Disposed on top of, 85 and embedded in the bridge-wall 16 of the boiler setting, at the base and in front of, the first bank 5 of circulating water tubes, and in proximity to the mud-drum 4, is a stationary jet-pipe 17, the same extending 90 across the boiler and substantially the full length of the bridge-wall. Radiating from peripheral openings of said pipe are nozzles 18 preferably disposed in transverse clusters of three spaced appropriate distances apart along the length of the pipe, the radial disposition of the nozzles of each cluster permitting the jets of steam (or other cleaning fluid) discharged therefrom to be projected radially outward from the 95 axis of the jet-pipe, the clusters being disposed in vertical planes at points opposite the spaces between the tubes T of the first bank 5 of circulating water tubes (Fig. 9), the discharge from any cluster of nozzles 100 assuming more or less the form of a flaring sheet of steam which readily penetrates the spaces between the tubes (5), the general direction of the blow from said nozzles conforming substantially to that of the draft 105 in the first pass above referred to. The steam supplied to the jet-pipe 17 is taken from the lower horizontal leg of the supply pipe P, the latter being tapped by a bent branch pipe or shunt 19 provided with a 110 hand valve V of the ordinary globe variety or its equivalent. The outer end of the pipe 17 traverses a bushing 20 embedded in the side wall of the boiler setting and closed by a plate 20'. To install the pipe 17, a suitable depression or basin is first formed in the bridge wall, said basin opening at the outer end opposite the bushing 20. This permits the pipe to be inserted into position, after which a filler 21 of refractory material or fire clay is packed around the pipe and around the nozzles 18, the discharge ends of the nozzles being flush with the crown or arched portion 115 of the filler (Fig. 10). The jet pipe 17 120

125

130

with its nozzles 18 constitutes the first blower unit of the series, and is fixed, no movement being imparted thereto during the blowing operation.

5 Leading from the front terminal of the lower horizontal branch or leg of the supply pipe P is a riser or header 22 whose upper end terminates at a point just below the baffle 11 between the shells 1 and 2. The 10 said riser is provided with any conventional form of hollow swivel joint 23 to the rotary member of which (well understood in the art) is coupled the outer end of the jet-pipe 24 of the second blower unit, said pipe being 15 disposed rearward of the bank of tubes 5 and parallel to and rearward of the shell 1 and parallel to the pipe 17. The outer end of the pipe 24 passes through a bushing 25 embedded in the side wall of the boiler setting and is partly supported in a bearing plate 26 closing the outer end of the bushing. The inner end of the jet-pipe is supported by a bracket 27 clamped to one of the water tubes 10 (Fig. 2) the semi-cylindrical upper terminal of said bracket which 20 forms the immediate seat or bearing for the pipe being received by the annular recess h formed between the flanges 28, 28, of a ring 29 set-screwed to the pipe at the proper point 25 to engage the bracket. The inner wall of the ring 29 is spaced from the peripheral surface of the jet-pipe 24 by means of inwardly projecting bosses or lugs t formed on the ring, said lugs engaging the pipe and 30 thereby leaving or forming circulating air spaces a between the lugs as best seen in Fig. 6. The jet-pipe 24 is protected by a fire-clay casing or sleeve 30 forming an air jacket, and preferably built up of a 35 series of sections making rabbet joints with one another, each section in the region of the joint between the sections being provided with spacing lugs or bosses t' leaving circulating air spaces a' (Fig. 5), said spaces 40 a', and the spaces a previously mentioned being in free communication with and forming part of the circulating air space s between the casing 30 and the pipe 24. The terminal sections of the casing 45 or jacket 30 are supported by the cap 31 and screw-cap 32 respectively, the former being adjustable and adapted to be set-screwed to the jet-pipe, and the latter screwed to the inner end of the pipe, this 50 arrangement serving to force the several sections of the jacket into firm engagement with one another as well as to clamp to the ring 29 the sections disposed on each side thereof. Preferably, and as shown in Fig. 55 3, the terminal jacket section engaging the cap 31 has a reduced end which is received by an annular recess or groove in the cap whereby the said section is shouldered against the cap. On the other hand, the 60 jacket section engaging the screw-cap 32 is preferably rabbeted and shouldered thereto as shown (Fig. 3). These details may however be altered without in any wise affecting the nature or scope of the present invention. Traversing the outer portion of 70 the jet-pipe 24 or that projecting beyond the bearing plate 26 is a bent vent-pipe 33 the outer end of which is open to the outer air through the peripheral wall of the jet-pipe at a point beyond the air jacket, the 75 inner end of the vent-pipe terminating behind the cap 31 and discharging through the peripheral wall of the jet-pipe into the circulating air space s between the jacket 30 and jet-pipe, the inner terminal of the jacket 80 being provided with a series of circularly disposed peripheral vent openings or ports 34 discharging into the combustion chamber of the boiler. The jet-pipe 24 is equipped with a longitudinal row of peripheral jet 85 nozzles 35 which extend across the air space s and penetrate and discharge through the walls of the jacket 30, the said nozzles serving to assist in securing the jacket to the jet-pipe, the two rotating as a unit when 90 rotation is imparted to the jet-pipe. Rotation may be imparted to the jet-pipe 24 in any suitable mechanical manner, the method employed in the present illustration consisting of a chain sheave-wheel 36 coupled to 95 the rotary member or element of the swivel joint 23, said member being coupled as previously stated to the jet-pipe. By imparting rotation to the sheave-wheel it follows that rotation will necessarily be imparted to 100 the pipe 24 and jacket 30, the two rotating as a unit about a common axis. The sheave-wheel 36 is operated by an endless chain 37 hanging within easy reach of the engineer or operator. Like the branch 19, the riser 105 22 is provided with a hand valve V where necessary, a drain valve or cock 38 being positioned at the lower end of the bottom horizontal leg of the pipe P for carrying off any water of condensation as well understood in the art. The jet nozzles 35 are so disposed or spaced along the pipe 24 as to sweep in vertical longitudinal planes between the tubes 10, whereby upon rotation of the pipe the cleaning jets will play in the 110 spaces between said tubes, and in the spaces between the tubes in the upper region of the first bank of tubes 5. The draft of the boiler furnace will naturally and at all times induce a flow of cool atmospheric air 115 through the vent pipe 33, and air space s and into the combustion chamber through the vent nozzles 34, so that overheating or burning out of the pipe 24 is prevented. The air jacket around the pipe will always maintain the same at a temperature sufficiently low to prevent burning of the pipe, yet, the air being heated in its passage through the space s will not cause any material drop in 120 the temperature of the steam blowing 130

through the jet-pipe to cause condensation, it being understood that in blowing or cleaning a boiler with steam, the steam should be as dry as possible to prevent baking or caking of the soot and ashes on the boiler tubes. The openings in the peripheral wall of the sleeve 30 through which the nozzles 35 are inserted are conical or outwardly flaring, and when the parts are assembled the 10 spaces around the nozzles are sealed with a filler 39 of refractory material or fire clay, so that no air can escape from the air jacket until the vents 34 are reached. In the type of boiler here shown and to which the present 15 cleaning system is applied, the most intense heat is in the region of the first and second blower units. For this reason the first unit is embedded in a layer of refractory material in the bridge-wall, and the 20 jet-pipe of the second unit is protected by an air jacket formed by a sleeve or casing of refractory material surrounding the pipe and leaving an air circulating space *s* as already described.

25 The third blower unit in the present installation operates between the first and second baffles, and is practically confined in its operation to the second bank of tubes 6. This unit is substantially as follows: Lead- 30 ing from the bottom horizontal leg of the supply pipe *P* is a riser or header 40 provided with a hand-valve *V*, and terminating at the top in a horizontal pipe or leg 40'. The pipe 40' is coupled to a *T* 41 at the 35 outer end of a stationary steam conducting or supply pipe 42 disposed rearward of the baffle 14 and at a suitable distance therefrom, the inner end of the pipe terminating at substantially the middle of the boiler. In 40 other words the pipe 42 terminates at a point opposite the middle (horizontally) of the middle bank of tubes 6, and substantially midway between the shell 2 and the mud-drum 4. The outer end of the pipe 42 passes 45 through a bushing 43 in the side wall of the boiler setting, the inner end of the pipe being connected as shown, to the gear case 44 of an angle gear joint (presently to be described), said case being preferably made in 50 two sections bolted together as shown (Fig. 14) and supported by a bracket 45 projecting through the vertical baffle 14, the bracket being itself clamped to a tube *T* adjacent the baffle. Traversing the pipe 42 and pro- 55 jecting through a stuffing-box 46 on the *T* 41 is a gear-shaft 47, the outer end of which is provided with a chain sheave-wheel 48 actuated by a chain 49 within easy reach of the engineer or operator. The inner end 60 of the gear-shaft is supported by bearings 50 in the gear case (Fig. 14) and terminates in a bevel pinion 51 which meshes with a bevel gear ring 52 set to rotate in a plane at right angles to the plane of rotation of the 65 pinion, whereby there is formed within the

gear case 44 (housing said pinion and gear ring) a gear-joint capable of transmitting rotation from the gear-shaft 47 to any other shaft or equivalent member whose axis of rotation is disposed at right angles to that of the gear-shaft. In the present instance this rotation is transmitted to the hollow shaft 53 to which the gear ring is secured. The inner end of the hollow shaft 53 terminates in a spindle or bearing 54 supported by one of the sections of the gear case, the said shaft being provided with peripheral circulating openings *o* adjacent the bearing 54. The outer projecting portion of the hollow shaft 53 terminates in a flange 55 to which is bolted the ring 56 into which the adjacent end of the rotary jet-pipe 57 is screwed, an opening *O* being formed in the baffle 14 to accommodate said pipe. The opposite end of the pipe 57 is closed by a cap 58 which is provided with a spindle 59, said spindle being supported by a strap 60 clamped about one of the tubes *T* forming the front row of the middle or second bank of tubes 6. The hollow shaft 53 operates in a stuffing-box 61; and the gear-shaft 47 is preferably connected to the bevel pinion 51 through a flexible joint 62 as shown (Fig. 14). The jet-pipe 57 operates at the center of the middle bank of tubes, and has rotation imparted thereto by the hollow shaft 53 to which it is coupled and with the axis of which the axis of the jet-pipe is coincident. The said jet-pipe 57 is disposed at right angles to the jet-pipes 17 and 24, being moreover inclined to the horizontal substantially the same number of degrees that the middle bank of tubes inclines to the vertical, so that the plane of rotation of said pipe is substantially parallel to the pitch of the middle bank of tubes. The said jet-pipe 57 is provided with peripheral radially discharging nozzles 63 on the order of the nozzles 18 and 35, said nozzles 63 being disposed in the transverse spaces between the tubes (or spaces between the transverse rows of tubes) of the second or middle bank of water tubes, whereby upon rotation being imparted to the jet-pipe, the nozzles will project the cleaning fluid (steam) into the spaces between the tubes in planes substantially parallel to said spaces and parallel to the pitch of the tubes. It may be stated in passing that the steam finds its way to the jet-pipe 57 through the hollow shaft 53, into which it passes from the riser 40, through the stationary supply pipe 42, the latter discharging into the gear-case 44 in which the steam freely circulates around the gear-shaft 47, flexible joint 62 and bevel pinion 51, flowing thence through the openings *o* of the hollow shaft 53 and into the jet-pipe 57 (Fig. 14). Rotation imparted to the gear-shaft 47 from the wheel 48 is necessarily imparted to the jet-pipe 57 in consequence 130

whereof the nozzles 63 will sweep and discharge the steam in the paths previously described.

The fourth and last blower unit of the series is substantially the same as unit number two, with the exception of the air jacket, it being understood that units numbers three and four require no air jackets, being located in regions where the temperature of the gases is insufficient to exert any material destructive effects on the jet-pipes. The fourth unit may be described as follows: Leading from the bottom horizontal leg of the supply pipe P is a riser or header 64 provided with a hand-valve V, said riser terminating at the top in a hollow swivel joint 65 to the rotary member of which is secured at one end the chain sheave-wheel 66 provided with an operating chain 67, the other end of the rotary member having coupled thereto the outer terminal of the transversely disposed jet-pipe 68 whose inner end is closed by a cap 69. The outer end of the jet-pipe passes through a bushing 70 in the side wall of the boiler setting, said bushing being closed along the outer face of the wall by a plate or ring 71 forming a bearing for the jet-pipe. The pipe is supported at its inner end by a bracket 72 clamped to one of the tubes T of the third bank of tubes 7, the said jet-pipe running parallel to said bank across the boiler and rearward of and adjacent to the lower end of said bank and at a suitable distance rearward of the mud-drum 4. The jet-pipe 68 is likewise parallel to the pipes 17 and 24 and perpendicular to the jet-pipe 57 of the third unit. The jet-pipe 68 is provided with a row of nozzles 73 on the order of the nozzles of the jet-pipes of the previous units described, said nozzles 73 being spaced so as to project the cleaning fluid into the spaces between the tubes T of the third bank of tubes 7, the cleaning fluid (steam) reaching said nozzles by way of the riser 64, the hollow swivel joint 65 (which may be of any approved type known to the art) and the jet-pipe 68. The operation of the blower is substantially as follows: As well understood in the art the jets of steam (or other fluid) escaping from the jet-pipes and impinging against the heating surfaces of the tubes (and drums) blow off the soot and other accumulations deposited thereon by the gases in their travel from the fire box rearward through the combustion chamber of the boiler toward the exit flue E. In the present embodiment of my invention the jet-pipe 17 of the first blower unit is stationary, the ports or nozzles 18 being so directed as to project the steam jets radially upward in parallel vertical planes into and through the spaces between the first bank of tubes 5, these planes of projection as obvious from Figs. 1, 9, and 10, being longitudinally of

the boiler or parallel to the side walls of the setting between which the drums 1, 2, 3, and 4 are mounted. The jets of steam thus projected take the general upward direction of the fire gases through the first gas pass, 70 the tubes being cleaned or "blown" well up toward and perhaps above the upper end of the first baffle 12. The jet-pipes 24, 57, and 68 entering into the construction of the second, third, and fourth blower units respectively, are all freely rotatable about their respective axes a full three hundred and sixty degrees, though in practice units numbers two and four are not, and in fact need not be rotated a full circle to fulfil their proper functions. In practice the air jacketed jet-pipe 24 (the pipe and its jacket 30 rotating as a unit) is rotated through an arc sufficient to cause the jets of steam issuing from the nozzles 35 to be projected into 80 and through the spaces between the tubes 10, and into and through the spaces between the upper portions of the tubes of the first bank of tubes 5, or those portions above the upper end of the baffle 12. By rotating said 90 pipe 24 in proper direction, we may cause the steam jets to be projected obliquely downward and rearward into and through the spaces between the upper portions of the tubes 6 of the middle bank as clearly apparent from Fig. 1. To clean the tubes 10 and the upper portions of the tubes of the first and second banks as described, we need not rotate the jet-pipe 24 a full three hundred and sixty degrees. A half revolution 95 will suffice to enable the steam jets to reach the portions of the tubes designed to be cleaned by this unit. Like in the first unit, the planes of projection of the steam jets from the second unit are longitudinal of the 100 boiler (the term "longitudinal" herein being used to designate the general direction from the fire box B toward the gas exit E) and at right angles to the general planes of inclination or pitch of the tubes. The jets directed against the upper portions of the first bank of tubes 5 while in a measure acting against the upward draft in the first gas pass they at the same time intensify the downward draft in the second gas pass, so 110 that the general direction of the draft is not interfered with. Of course in blowing down toward the upper portions of the middle bank of tubes 6 the blowing action is wholly in favor or in the general downward direction, 115 of the second gas pass, so that in that case the draft is materially intensified. We now come to the jet-pipes 57 of the third blower unit. As already fully described, rotation is imparted to this pipe 120 from the gear-shaft 47 through the angle gear-joint in the gear case 44, and through the hollow shaft 53 which in effect is an extension of said jet-pipe. In practice the pipe 57 is rotated a full three hundred and sixty 130

degrees, the steam jets issuing from the nozzles 63 thereof being thereby projected into the spaces between the tubes of the second bank in transverse planes substantially parallel to the dip or pitch of the tubes, said planes of projections being at right angles to the vertical longitudinal planes of projection of the jets of steam from the jet-pipes 17 and 24 of the first and second blower units respectively. This follows from the fact that the sweep of the nozzles 63 of the third blower unit is transverse to the sweep of the nozzles 35 of the second blower unit, and transverse to the planes of the steam sheets formed by the successive clusters of radial nozzles 18 disposed transversely across the periphery of the jet-pipe 17 of the first blower unit. In practice the pipe 57 may be rotated back and forth until the steam jets have cleaned the tubes of all accumulations of soot, ashes and other deposits. When the nozzles 63 are pointing downward the downdraft in the second gas pass is materially intensified as obvious from the drawings. When these nozzles point upward the general line of draft is not disturbed because of the fact that in blowing upward along the tubes of the second bank the vacuum produced below the jet-pipe 57 draws in a measure the gases of the natural draft downward (in the general direction of the second pass) between the baffle 12 and the front transverse row of tubes of the middle bank of tubes 6, so that here again the natural draft instead of being interfered with is in fact not materially disturbed if at all. A complete rotation of the pipe 57 will cause the jets from the nozzles 63 to reach every portion of the surface of the tubes of the middle bank and clean them thoroughly. The upper portions of these same tubes may likewise be cleaned by the jets from the pipe 24 of the second unit as already described; and since the jets from the pipe of the second unit play against the tubes (of the middle bank) at right angles to the planes of projection of the jets from the pipe 57, it follows that the jets will reach all around the tubes and a most thorough and complete cleaning of the upper half of the middle bank of tubes may thus be effected. In the same way and for a like reason an equally thorough cleaning of the lower half of this bank may be effected, it being remembered that the planes of projection of the jets from the pipe 68 of the fourth or last unit are likewise at right angles to the planes of projection of the jets from the pipe 57. In other words by imparting the required degree of rotation to the jet-pipe 68 the nozzle 73 thereof can be made to project the jets issuing from them (into the spaces between the lower portions of the tubes of the third bank 7) well into

the spaces between the lower half of the tubes 65 of the middle bank. It is of course not necessary under ordinary service conditions to make use of either the second or fourth blower unit to clean the middle bank of tubes, the jet pipe 57 of the third blower 70 unit being sufficient to take care of this bank; but there may be circumstances where the engineer might find it desirable to supplement the action of the pipe 57 by the pipes 24 and 68 of the second and fourth 75 units respectively, as above explained. The fourth unit is in the majority of cases restricted in its operation to the third bank of tubes 7. It will be seen (Figs. 1, 15, 16) that a rotation of the jet pipe of this unit 80 through a proper arc will cause the nozzles 73 thereof to project the cleaning fluid into and through the spaces between the tubes of this bank, the paths of projection being in longitudinal vertical planes the same as the 85 jets issuing from units numbers one and two. The angle or arc through which the jet pipe of any rotatable unit is rotated in the blowing operation is a matter of judgment on the part of the operator, but of course the 90 rotation should always be sufficient to cause the cleaning fluid to reach as much of the exposed heating surfaces of the bank of tubes being cleaned, as is possible with the particular unit under manipulation. It will 95 be seen that banks 5 and 7 are cleaned by jets projected in vertical longitudinal planes from blower units numbers one, two and four; and the middle bank 6 may be cleaned either wholly by unit number 3 (pipe 57) 100 which projects the cleaning fluid in transverse planes parallel to the pitch of the tubes of said bank, or the action of said third unit may be supplemented by the jet-pipes 24 and 68 of units two and four 105 wherein the paths of projection of the fluid are in vertical longitudinal planes, or transverse to the planes of the jets projected by the jet-pipe 57. It is further obvious that while the several units may be blown simultaneously, this method is not as a rule resorted to, as it would lead to a too great consumption of steam at one time which is neither desirable nor necessary. The particular order of manipulation of the several units (each being provided with a hand valve V) rests with the engineer. The natural order of course is to begin with unit number one and end with unit number four. The state of soot accumulation may be such 110 that it may not be necessary to operate all the units every time the boiler is blown or cleaned. It may be that the accumulation on a given bank of tubes may be negligible whereas on another bank it may be considerable. Of course to clean the boiler thoroughly and completely all the units should be blown, the particular sequence fol- 115 120 125

lowed being in the discretion of the engineer. The safest plan perhaps to pursue would be to blow each unit in regular sequence beginning with number one and ending with 5 number four. It is to be understood that the purpose of air jacketing the second blower unit is merely to prevent the burning out of the pipe 24 by the hot gases, the same reason applying for embedding the pipe 17 of the 10 first unit in a layer of refractory material 21. The air escaping from the air jacket of the second unit into the combustion chamber does not take part in the cleaning operation, the venting of the jacket being of course necessary to keep the air circulating around the 15 jet-pipe 24. It is to be noted that the details of the construction here shown may be altered in many particulars without departing from the nature or spirit of the invention. Features shown but not alluded to are 20 well understood in the art and need not be described in the present connection. It is further to be understood that the application of my invention or parts thereof is not 25 to be restricted to cleaning Stirling boilers, but with certain changes of detail falling within the purview of the skilled mechanic the invention may be applied to other types 30 of water tube boilers, as for example the Babcock & Wilcox, commonly known as the B. & W. water tube boiler.

Having described my invention what I claim is:

1. In a boiler of the character described, 35 a jet-pipe provided with peripheral openings, a casing or sleeve surrounding the same and spaced therefrom and forming an air-jacket around the pipe, the casing being provided with vent openings, and a vent- 40 pipe disposed in the jet-pipe having an intake terminal open to the atmosphere through the wall of the jet-pipe at a point beyond or outside the casing, and having a discharge terminal opening through the wall of the

jet-pipe into the air-jacket formed by the 45 casing.

2. A blower unit for boilers comprising a rotary jet-pipe provided with nozzles projecting beyond the peripheral surface of the pipe, and having an intake end for the cleaning fluid, an adjustable ring on the pipe adapted to be secured to the pipe at any predetermined point, terminal caps on said pipe, a sleeve or casing comprising a plurality of sections spaced from the pipe and forming an air-jacket for the same, the casing sections being supported between the intermediate adjustable ring and the terminal caps aforesaid, said sections and the adjustable ring being provided with bosses or 50 lugs on their inner surfaces for engaging the periphery of the pipe, said bosses being spaced circularly apart to leave spaces establishing intercommunication with the air-jacket spaces on either side thereof, the 55 intermediate ring being provided with a peripheral depression to receive a suitable bearing, suitable vent openings being formed in the jacket wall in proximity to the inner terminal of the blower unit, a vent-pipe disposed at the outer terminal of the unit within the jet pipe, the intake end of said vent-pipe opening to the atmosphere through the wall of the jet-pipe at a point outside the air jacket, and having a discharge end open 60 to the air jacket through the wall of the jet-pipe at a point rearward of the front jacket-supporting cap, the blower nozzles leading from the walls of the jet-pipe across the air-jacket and discharging through the walls of 65 the casing aforesaid, said casing being composed of refractory material.

In testimony whereof I affix my signature, in presence of two witnesses.

LEO JNO. BAYER.
